[57] CLAIM

The ornamental design for a vacuum breaker for use with a bidet, as shown and described.

DESCRIPTION

FIG. 1 is a rear perspective view of a vacuum breaker for use with a bidet showing my new design;

FIG. 2 is a front elevational view thereof;

FIG. 3 is a left side elevational view thereof, the right side being a mirror image thereof;

FIG. 4 is a rear elevational view thereof;

FIG. 5 is a top plan view thereof; and

FIG. 6 is a front perspective view thereof.
